UNITED STATES PATENT OFFICE.

KARL BAUMANN, OF URMSTON, ENGLAND, ASSIGNOR TO THE BRITISH WESTINGHOUSE ELECTRIC AND MANUFACTURING COMPANY LIMITED, A COMPANY, OF GREAT BRITAIN.

SUPPORT FOR CONDENSERS.

1,277,830.

Specification of Letters Patent. Patented Sept. 3, 1918.

Application filed January 31, 1917. Serial No. 145,706.

To all whom it may concern:

Be it known that I, KARL BAUMANN, a citizen of the Confederation of Switzerland, and a resident of Urmston, in the county of 5 Lancaster, England, have invented a new and useful Support for Condensers, of which the following is a specification.

This invention relates to steam condensers, especially condensers used in connection 10 with steam turbines in which the condenser is supported immediately below and attached to the outlet of the exhaust casing of the turbine.

One of the objects of the present invention 15 is to provide an improved construction of condenser in which the expansion piece or joint, usually employed between the condenser shell and the exhaust casing of the turbine, is rendered unnecessary.

20 Another object of the invention is to provide an improved construction of condenser in which the condensing surface, for instance the tube nest, may be brought nearer to the last row or rows of blades from which 25 the steam leaving the turbine flows, thus shortening the path for the steam flowing from the turbine to the condenser.

A further object of this invention is to 30 reduce the combined height of the turbine and condenser.

The shells of condensers as usually constructed heretofore have little or no flexibility such as will allow of movements due to expansion taking place in a vertical direction, necessitating the employment of an 35 expansion piece or joint between the condenser shell and the exhaust outlet of the turbine. This lack of flexibility in the shells of such condensers is due chiefly to the supporting feet for the condenser shell being 40 too far apart in a transverse direction and to the condenser inlet being too wide relatively to the width of the shell.

According to this invention either sub- 45 stantially the entire shell of the condenser is made flexible or a rigid shell is connected to portions of the condenser supported from the foundations by flexible joints or pieces in place of a flexible joint or piece being inserted between the condenser shell and the 50 exhaust outlet of the turbine as hitherto.

Flexibility of the shell in a vertical direction is obtained according to this invention, by arranging that the supporting feet 55 are secured to the condenser over a relatively

small portion only of the transverse width of the shell, and by making the steam inlet thereto relatively narrow.

Several forms in which the invention may be carried into effect are shown more or less 60 diagrammatically by way of example in the accompanying drawings in which Figure 1 is a longitudinal sectional view and Fig. 2 a cross sectional view of a condenser constructed in accordance with the invention. 65 Fig. 3 is an explanatory view hereinafter referred to. Fig. 4 is a cross sectional view and Figs. 5, 6 and 7 are fragmentary views showing alternative constructions. Fig. 8 is a cross sectional view and Fig. 9 a longitudinal sectional view of another form of condenser constructed in accordance with the invention. Fig. 10 is a detail view hereinafter explained.

Referring now to Figs. 1 to 3, the shell 11 75 of the condenser is supported from below by feet 13 which extend as shown over a relatively small portion of the width of the shell and are bolted to the foundations 12. Preferably the feet 13 are bolted to the foundations at or about midway of the length of the shell only although if desired additional bolts may be provided nearer the ends of the feet 13 to hold the condenser down to the foundations, but such bolts should preferably be of the sliding type. By securing the condenser to the foundations in this manner it may expand lengthwise sliding 80 on the foundations 12. The sagging plates which support the tubes, one of which is 85 shown at 14, are secured to the condenser shell by lugs 15 at their lower edges only, the upper parts of said plates 14 being maintained in position by lugs 16 on the condenser shell of such a form that the sagging 90 plates may slide between them. Alternatively the sagging plates may be maintained in position by distance rods and nuts, the rods being attached at one or both ends to the tube plates or water boxes. 95

The exhaust outlet of the turbine is shown 100 at 17 and is provided with a flange 18 corresponding with a flange 19 around the inlet to the condenser. In order to insure a tight joint between said flanges, as well as to prevent sliding, they are preferably provided with a spigot and groove or are secured together by fitting bolts. The exhaust outlet 17 of the turbine and the inlet to the condenser are made long and narrow, as shown, 110

the major axis of the exhaust outlet being parallel with the axis of the condenser.

With the construction above described the shell of the condenser will be sufficiently flexible to allow of movements in a vertical direction taking place due to expansion, the shape assumed by the shell under these conditions being shown by the dotted lines in Fig. 3, and the employment of the usual 10 expansion joint or piece between the exhaust outlet 17 of the turbine and shell 11 of the condenser is rendered unnecessary.

The portions of the condenser shell attached to the exhaust outlet of the turbine 15 and especially those portions of the shell lying between said outlet and the tube plates or end boxes of the condenser may be given greater flexibility in the manner shown in Figs. 4 and 5 in which the parts 21 of the 20 upper portion 20 of the shell lying between the exhaust outlet 17 of the turbine and the tube plates 22 are suitably curved to provide for movements due to expansion taking place. It is, however, not essential that the 25 portions 20 and 21 should be made flexible as they may be made rigid providing sufficient flexibility is obtained in the remaining body portion of the shell. Such a construction is shown in Figs. 6 and 7.

Referring now to Figs. 8 and 9, the turbine with which the condenser is adapted to be employed is shown at 24 in outline. The major portion of the shell 25 of the condenser is made rigid, being attached directly 35 to and hung from the exhaust outlet 17 of the turbine casing. A portion 34 of the shell adjoining the water box 26 is supported directly on the foundations 12, another portion 27 of the shell connected with the other water box 28 being also supported on the foundations 12. The tubes 29, tube plates 30 and sagging plates (not shown) are supported from those portions of the condenser attached to the foundations and their weight 45 is consequently carried by the foundations 12, the casing of the turbine being thus relieved of all weight except that of the rigid portion 25 of the condenser shell. In the construction shown in Figs. 8 and 9 a central longitudinal web 31 extends from one water box 26 to the other 28 and serves to take the atmospheric thrust on the condenser. Flexible expansion pieces 32, 33 connect the rigid condenser shell 25 with 50 those portions 27, 34 of the condenser directly supported on the foundations 12, so as to allow of movements of the shell 25 due to expansion taking place.

In place of the longitudinal web 31 a suitable frame or stretcher may be employed to connect the two ends of the condenser which are supported on the foundations. Alternatively thrust rods movably connected be-

tween the end portions 27, 34 of the condenser supported on the foundations and the 65 rigid portion 25 of the shell and extending across the expansion pieces 32, 33 may be provided for taking the atmospheric thrust and preventing collapse of the flexible expansion joints 32, 33.

With the construction shown in Figs. 8 and 9 the sagging plates are not attached to the shell 25 of the condenser but to a web or frame extending along the length of the condenser and connected with the end portions 27, 34 thereof which are supported on the foundations. Said web or frame may conveniently be the same as the web 31 provided for taking the atmospheric thrust, the sagging plates being attached thereto by 80 lugs or in some other suitable way.

Fig. 10 shows an alternative form which the expansion pieces 32, 33 may take instead of that shown in Fig. 9. The expansion pieces 32, 33 must however be of such a form as to allow of expansion taking place both in a vertical and in a horizontal direction. Either of the forms shown in Figs. 9 and 10 will allow of this.

I claim as my invention:

1. A steam condenser adapted to be supported immediately below and attached to the outlet from the exhaust casing of a steam turbine in which the supporting feet by which the condenser is attached to the foundations are secured to the condenser over a relatively small portion only of the transverse width of the condenser shell, and the steam inlet to the condenser is made relatively narrow, substantially as and with the 100 objects set forth.

2. A steam condenser adapted to be supported immediately below the exhaust outlet of a steam turbine, comprising a horizontal shell having a relatively narrow steam inlet 95 and supporting feet adapted to be attached to the condenser foundations and which are secured to said shell over a relatively small portion only of the transverse width thereof.

3. In combination with a steam turbine 110 and a condenser foundation beneath the same and spaced therefrom, a condenser having a horizontal shell and a relatively narrow steam inlet attached to the exhaust of said turbine, and condenser shell supporting feet attached to said foundation and to said shell and extending over a relatively small portion only of the transverse width of said shell.

In testimony whereof I have hereunto 120 subscribed my name this second day of January, 1917.

KARL BAUMANN.
